UNITED STATES PATENT OFFICE

134,585

DESIGN FOR A THERMOCOUPLE UNIT

Arthur T. Ball, Wallingford, Conn.

Application May 26, 1942, Serial No. 107,014

Term of patent 14 years

To all whom it may concern:

Be it known that I, Arvid P. Zetterberg, a citizen of the United States and resident of Wallingford, in the county of New Haven and State of Connecticut, have invented a new, original, and ornamental Design for a Thermocouple Unit, of which the following is a specification, reference being had to the accompanying drawing, forming a part thereof.

Fig. 1 represents a side elevational view of a

thermocouple unit embodying my new design; and

Fig. 2 represents a bottom plan view thereof.

The device is circular in cross section except for the hexagonal part of the mounting coupling.

I claim:

The ornamental design for a thermocouple unit, substantially as shown and described.
